UNITED STATES PATENT OFFICE.

JOSEPH P. HARTNETT, OF ROCKAWAY BEACH, NEW YORK, ASSIGNOR TO CARTIER, INC., A CORPORATION OF NEW YORK.

DESIGN FOR AN ARTICLE OF MANUFACTURE.

57,970.

Specification for Design.

Patented May 24, 1921.

Application filed September 23, 1920. Serial No. 412,405. Term of patent 7 years.

To all whom it may concern:

Be it known that I, JOSEPH P. HARTNETT, a citizen of the United States, residing at Rockaway Beach, in the county of Queens and State of New York, have invented a new and original ornamental decorative Design for an Article of Manufacture, of which the following is a specification, reference being had to the accompanying drawing forming part thereof.

The drawing shows the decorative design of this invention applied to a pendant.

I claim:

The ornamental design for an article of manufacture, as shown.

JOSEPH P. HARTNETT.
